HAROLD A. WHEELER, OF JACKSON HEIGHTS, NEW YORK, ASSIGNOR TO HAZELTINE CORPORATION, A CORPORATION OF DELAWARE

ELECTRIC COUPLING CIRCUITS

Application filed August 20, 1930. Serial No. 476,541.

This invention relates to high frequency electric coupling circuits tunable over a range in frequency and adapted more especially for interconnecting successive elements of a high frequency thermionic amplifier or radio system.

The coupling circuits of the present invention are characterized in that the voltage amplification produced thereby is caused to vary automatically with the frequency of tuning in a manner which is under the control of the designer; the design in general being preferably such as to produce a substantially constant amplification, i. e. uniform sensitivity throughout the tunable frequency range.

With an elementary type of high frequency coupling circuit, of which a two-winding transformer having a tunable secondary is a typical example, the variation in amplification with frequency is not under the control of the designer, but increases with frequency throughout the tunable range, in a manner well understood, so that the resulting sensitivity is widely different at the lower and higher frequencies.

In the elementary type of coupling circuit referred to above, there exists between the primary and tunable secondary circuits, a degree of coupling which is substantially constant throughout the tunable range, a condition which is partially responsible for the mentioned increase in amplification with frequency. The present invention avoids the resultant disadvantages of the elementary coupling circuit by the proper inclusion of certain reactance elements adapted to provide an effective coupling between the input and tunable output circuits which automatically decreases with increase in the tuning frequency and thereby may be proportioned to offset, wholly or in part, the factors operative to produce an increase in amplification with frequency. Coupling circuits broadly operative in accordance with the principles disclosed herein, but differing from the pres-

ent invention both as regards the circuit connections utilized and the specific modes of operation involved, are set forth in Patent No. 1,763,380 issued to C. E. Trube, and in his co-pending applications Serial No. 50 101,906, filed April 14, 1926 and Serial No. 120,045, filed July 2, 1926.

The coupling circuits of the present invention comprise the following essential elements, namely: a tunable secondary circuit 55 including a fixed inductive winding and variable capacity bridged between a pair of output terminals, and a primary circuit including in closed series connection in the order named, a portion or all of the secondary 60 winding, a fixed capacity, a fixed inductance, and a primary winding magnetically coupled to the secondary winding and of relatively small magnitude compared to the fixed inductance. The primary winding is so poled 65 as to give coupling from the primary to the secondary circuit in additive relation to the coupling to the portion of the secondary winding which is included in the primary circuit. Input terminals are connected to the 70 primary circuit between the fixed capacity and inductance and between the primary and secondary windings, respectively, so that there is provided a pair of parallel paths, one path containing the fixed capacity and the 75 portion of said secondary winding included in the primary circuit, while the other path contains the fixed inductance and the primary winding magnetically coupled to the secondary.

An additional capacity may or may not be connected directly between the input terminals, according to whether or not there is already present sufficient capacity for the purpose explained below. On the other 85 hand, sufficient capacity may exist between these terminals due to the type of input connected thereto. In any event, the resulting capacity associated with the inductance of the primary circuit, including the fixed ca- 90

5 capacity of the closed series circuit which is connected in shunt with the primary circuit, as well as any capacity existing between the input terminals, should be such as to render the primary circuit resonant at a frequency lower but not greatly lower than the lowest frequency within the tunable range.

10 The objects attained by such design (1) provide an effective coupling between primary and secondary circuits which automatically falls off as the frequency of tuning is increased, at a rate proportioned to produce a desired variation in amplification with frequency, and (2) control the variations in input impedance of the coupling circuit throughout the tunable range in such manner as to insure the desired performance.

15 The manner in which the results of the present invention are attained will be more clearly understood upon detailed consideration of the circuit connections set forth in the drawings, of which:

20 Figs. 1 and 2 show in diagrammatic form two modifications of elementary coupling circuits in accordance with this invention.

25 Fig. 3 shows the coupling circuit of Fig. 2 as utilized for connecting an antenna circuit with the input to a thermionic tube;

30 Fig. 4 shows diagrammatically the coupling circuit of Fig. 1 as employed for interconnecting a pair of screen-grid thermionic tubes in cascade relation; while

35 Figure 5 shows an interstage connection employing triode tubes wherein the coupling circuit is arranged in conjunction with a suitable capacity to provide neutralization of the interelectrode tube capacity.

40 Like elements are similarly designated in the several figures.

45 Referring to the drawings, the coupling circuit of Fig. 1 comprises a resonant secondary circuit consisting of a fixed inductive winding L and a variable tuning condenser C bridged between output terminals, and a primary circuit associated with the input terminals I including in closed series connection in the order named, the entire winding L , a fixed capacity C_1 , a fixed inductance L_2 and a primary winding L_3 magnetically coupled 50 to the secondary winding L as indicated, and of relatively few turns compared to the fixed inductance L_2 . The winding L_3 is so poled as to give coupling from the primary to the secondary circuit in additive relation with 55 the coupling to the winding L .

60 A pair of input terminals I are connected between the fixed capacity C_1 and the inductance L_2 and between the primary winding L_3 and the secondary winding L respectively, thereby providing the parallel paths between the input terminals one of which contains the fixed capacity C_1 and secondary winding L , while the other path contains the fixed inductance L_2 and the primary winding L_3 .

65 The capacity C_2 shown dotted is intended

to represent the entire capacity connected between the input terminals during operation of the circuit, including any capacity effects due to the input impedance connected thereto together with the capacity of a supplementary condenser which may be connected between these terminals.

70 The capacities C_2 and C_1 together with any additional capacity effects associated with the primary circuit inductance which includes the elements L_2 , L_3 and L , should be such as to render the primary circuit resonant at a frequency lower, but not greatly lower, than the lowest frequency in the tunable range as determined by adjustment of condenser C_1 . 75 It is not essential to the operation of the circuit that a capacity C_2 exist between the input terminals I . In the event that the capacity C_2 is zero, however, it is required that the capacity C_1 be of such magnitude as to render the primary circuit resonant at the low frequency above specified.

80 The reactances of the primary circuit are so proportioned that the path between the input terminals containing the elements C_1 and L is capacitatively reactive throughout the tunable range, and hence of decreasing impedance for increases in the tuned frequency; whereas the path containing elements L_2 and L_3 being of necessity inductively reactive, the impedance thereof increases with the tuning frequency. Thus, the windings L_3 and L produce effects in the secondary circuit which vary in opposite fashion with the tuning adjustment, the resultant effect being proportioned to produce an effective coupling between primary and secondary circuits which automatically decreases with increasing tuning frequency, in a manner which with sufficient accuracy is expressed 100 by the following equation:

$$(1) \quad m = m_3 + \frac{m_4}{\left(\frac{f}{f_2}\right)^2 - 1} \quad 110$$

where f_2 is the resonant frequency of the primary circuit, f the frequency of tuning, while m_3 and m_4 are constants expressed by

$$(2) \quad m_3 = \frac{LC_1}{C_1 + C_2} \quad 115$$

$$(3) \quad m_4 = M_3 + \frac{LC_1}{C_1 + C_2} \quad 120$$

In Equations (2) and (3) the symbols L , C_1 and C_2 have the significance shown in the drawings; while M_3 is the mutual inductance between windings L_3 and L . It will be observed from Equation (1) that the effective 125 coupling must necessarily decrease with increase in the tuned frequency.

The modification of Fig. 2 differs from Fig. 1 in that condenser C_1 is connected to an intermediate point of winding L so that only a 130

portion L_1 of the secondary winding L is included in the primary circuit.

The operation of the circuit of Fig. 2 is substantially identical with that of Fig. 1.

5 The coupling constants m_3 and m_4 , however, are changed from those given in Equations (2) and (3) to the following expressions:

$$(4) \quad m_3 = \frac{M_1 C_1}{C_1 + C_2}$$

$$(5) \quad m_4 = M_3 + \frac{M_1 C_1}{C_1 + C_2}$$

10 where M_1 is the mutual inductance between windings L_1 and L , the significance of the remaining symbols being the same as for Equations (2) and (3).

15 In Fig. 3 the input terminals I of the coupling circuit of Fig. 2 are connected to an antenna 1 and a ground 2, respectively, while the output terminals are connected to the grid and cathode, respectively, of a thermionic tube V_1 . The capacity C_2 of Figs. 1 and 2 comprises in Fig. 3 the effective antenna-to-ground capacity of the antenna 1 which in conjunction with capacity C_1 renders the primary circuit inductance comprising elements L_1 , L_2 and L_3 resonant at a frequency below the tuning range.

20 In Fig. 4 wherein the coupling circuit interconnects a pair of screen-grid tubes, V_1 and V_2 , in cascade relation, the input terminals I are connected to the anode and cathode respectively of tube V_1 ; while the 25 output terminals O are connected between grid and cathode respectively of tube V_2 . A battery B for supplying space current to tube V_1 is serially interposed in the shunt path containing elements L_2 and L_3 with the negative battery terminal joined to the grounded conductor 3. The capacity C_2 of Fig. 2 comprises in Fig. 4 the anode-to-ground capacity of tube V_1 which together with capacity C_1 renders the inductance of the primary circuit resonant at the mentioned low frequency.

30 The coupling circuit of Fig. 5 interconnects a pair of triode tubes in cascade relation, each tube having anode, cathode and grid electrodes only. In order to neutralize 35 grid-to-anode capacity of tube V_2 , a condenser C_n is connected from the anode thereof to the point between the fixed inductance L_2 and the primary winding L_3 , this point being of opposite polarity to that of the upper terminal of winding L to which the interelectrode capacity C_g is connected. The neutralization is accomplished in the manner disclosed in Patent No. 1,489,228 issued to L. A. Hazeltine, April 1, 1924.

40 In Fig. 5 the capacity C_2 comprises the anode-to-ground of the tube V_1 plus the capacity of the associated neutralizing condenser C_n which is effectively in parallel therewith, owing to the small inductance of the 45 winding L_3 .

While the coupling circuit of Fig. 2 is shown in all of the various modifications in Figs. 3 to 5, inclusive, it is to be understood that the coupling circuit of Fig. 1 might in each instance have been equally well employed, additional figures including such disclosure being deemed unnecessary.

50 It will be noted that in Figs. 3 to 5 inclusive the circuit arrangement is such that the rotor element of the tuning condenser may be grounded directly, constituting a very desirable feature in that it eliminates certain incidental couplings between the several parts of the amplifier.

I claim:

1. An electric coupling system comprising a tunable secondary circuit including a fixed secondary winding and variable capacity bridged between output terminals, and a primary circuit including in closed series connection in the order recited, at least a portion of said secondary winding, a fixed capacity, a fixed inductance, and a primary winding magnetically coupled to said secondary and of relatively few turns compared to said fixed inductance, an input terminal connected between said fixed capacity and inductance, and a second input terminal extending between said primary and secondary windings, the inductance included in said closed series circuit together with the associated capacities including any capacity bridged between said input terminals in the operation of said circuit, being resonant at a frequency slightly below the tunable range.

55 2. An electric coupling system comprising a tunable secondary circuit including a fixed secondary winding and variable capacity bridged between output terminals, and a primary circuit including in closed series connection in the order recited, at least a portion of said secondary winding, a fixed capacity, a fixed inductance and a primary winding of relatively few turns compared to said fixed inductance and magnetically coupled to said secondary winding, an input terminal connected between said fixed capacity and said fixed inductance, and a second input terminal connected between said primary and secondary windings, and a fixed capacity bridged between said input terminals, said fixed inductance together with the associated capacities being resonant at a frequency slightly below the tunable range for controlling throughout said frequency range the coupling between said primary and secondary circuits.

60 3. An electric coupling system comprising a tunable secondary circuit including a fixed secondary winding and variable capacity bridged between output terminals, and a primary circuit including in closed series connection in the order recited, at least a portion of said secondary winding, a fixed capacity, a fixed inductance, and a primary

winding magnetically coupled to said secondary winding and of relatively few turns compared to said fixed inductance, an input terminal connected between said fixed capacity and said fixed inductance, a second input terminal connected between said primary and secondary windings, said fixed inductance together with the associated capacities including any capacity bridged between 10 said input terminals in the operation of said circuit, being resonant at a frequency slightly below the tunable range, said primary and secondary windings having opposite polarities.

15 4. In a radio receiving system the combination of a high frequency electric coupling circuit comprising a tunable secondary circuit including a fixed secondary winding and variable capacity bridged between grid and cathode of a thermionic tube; and a primary circuit including in closed series connection in the order recited, at least a portion of said secondary winding, a fixed capacity, a fixed inductance and a primary winding 20 magnetically coupled to said secondary winding, an input terminal connected between said fixed capacity and said fixed inductance, a second input terminal connected between said primary and secondary windings the terminals of which thus joined are 30 of opposite polarity, and an antenna circuit connected to said input terminals, the inductance of said primary circuit together with the associated capacities including the capacity of said antenna effectively bridged between said input terminals, being resonant at a frequency below the tunable range, for automatically controlling throughout said 35 range the coupling between said primary and 40 secondary circuits.

5. A high frequency thermionic amplifier comprising the combination of an electric coupling circuit having a tunable secondary circuit consisting of a fixed secondary winding and variable capacity bridged between grid and cathode of a first thermionic tube, a primary circuit including in closed series connection in the order recited, at least a portion of said secondary winding, a fixed capacity, a fixed inductance, and a primary winding magnetically coupled to said secondary 50 a second thermionic tube having an anode connected between said fixed capacity and inductance, and a cathode connected between said primary and secondary windings the terminals of which thus joined are of opposite polarity, the inductance of said primary circuit together with the associated capacities including the anode-to-ground capacity of said second tube being resonant at a frequency slightly below the tunable range, for providing automatically throughout said range uniformly high degrees of amplification.

6. A high frequency thermionic amplifier

comprising the combination of an electric coupling circuit having a tunable secondary circuit including a fixed secondary winding and variable capacity bridged between grid and cathode of a first thermionic tube, a primary circuit including in closed series connection in the order recited, at least a portion of said secondary winding, a fixed capacity, a fixed inductance, and a primary winding magnetically coupled to said secondary 70 winding, a second thermionic tube having an anode connected between said fixed capacity and said fixed inductance, and a cathode connected between said primary and secondary windings the terminals of which thus joined are of opposite polarity, and a condenser proportioned to neutralize the anode-to-grid capacity of said first tube connected from the anode thereof to a point between said primary winding and said fixed inductance, said 80 fixed inductance together with the associated capacities including the anode-to-ground capacity of said second tube and said condensers being resonant at a frequency below the tunable range, for providing automatically 85 throughout said range uniformly high degrees of amplification in the operation of said amplifier.

In testimony whereof I affix my signature.
